UNITED STATES PATENT OFFICE

2,082,577

FASTENING DEVICE

Frederick K. Herschmann, New York, N. Y.

Application February 9, 1935, Serial No. 5,686

4 Claims. (Cl. 40—11)

This invention relates in general to fastening devices and more particularly to that class of fastening devices for mounting pictures, display articles and the like.

One of the objects of the invention is to provide a fastening device that may readily be applied to any type of surface for fast engagement therewith and yet be capable of holding an article in fixed position on the surface without perforating or otherwise damaging the article to be thus supported.

Another object is to provide such a fastening device for receiving conventional fastening elements for securing the device to the supporting surface.

Another object is to provide such a fastening device that the fastening element may be stamped out of it.

A further object is to so construct the fastening devices with stamped out fastening elements that the devices may consist generally of a tape that may be wound up on a spool, the fastening devices also being stamped out of the tape and separable from one another for using or dispensing purposes.

With the foregoing and other objects in view the invention resides in the combination of parts and in the details of construction hereinafter set forth in the following specification and appended claims, certain embodiments thereof being illustrated in the accompanying drawing, in which:

Figure 1 is a view in top plan of one form of my invention for holding the corner of an article;

Figure 2 is a view in section taken along line 2—2 through the supporting surface, the fastening device and the article supported;

Figure 3 is a view in perspective of one form of fastening device with a stamped out fastening element;

Figure 4 is a top plan view of a straight side fastening device;

Figure 5 is a detail view in perspective of one form of fastening device stamped out of a tape and having in turn stamped out fastening elements;

Figure 6 is a view in perspective of a wound up reel of fastening devices of the form shown in Figure 5;

Figure 7 is a view in perspective of a corrugated fastening device and supporting surface;

Figure 8 is a partial top plan view of a supporting surface and another form of fastening device employing vacuum cups;

Figure 9 is a view in section taken along line 9—9 of Figure 8;

Figure 10 is an enlarged view in perspective of a fastening device employing a vacuum cup and a removable fastening element.

Referring more particularly to the drawing, my invention may take the form illustrated in Figures 1 and 2. Here the supporting surface 1 may be a drawing board, display frame or the like. The fastening device is right angular in general form to substantially conform to one or more corners of the supporting surface. The 10 fastening device may be metallic or of some semi-rigid material. It should however be of springy material. It has a back plate 2 with a bent over portion looped at 3 and terminating at 4 in a spaced superimposed portion generally indicated 15 at 5. The back plate 2 may be provided with one or more elongated slots 6 extending upwardly from the lower margin 2' of the back plate. The upper extremity of the slots 6 terminate in rounded portions 7. This is for a matter of convenience for receiving the shank 8 of a fastening element, such as a tack, nail, screw or the like, the head of which is shown at 9. Thus the fastening element may be driven into the supporting surface either prior to or after the fastening 25 elements engage the slots in the plate of the fastening device.

As mentioned previously the primary purpose is to hold the picture or display card or the like in position. Such an article is indicated at 10. The 30 fastening device, being of springy material, has a tendency to grip the article 10 in the position shown in Figure 2. In order to augment this gripping tendency the plate 5, or the plate 2, may be provided with indentations, such as 35 shown respectively at 11 and 12. In case both plates are so indented the indentations may be made to oppose each other or made irrespective of the position of the other. The number of such indentations may vary for the required purposes. Furthermore, the inner adjacent surfaces of indentations 11 and 12 may be made slightly knurled and the illustration in Figure 2 may be considered as a sufficient showing of this 40 feature. This gives an added gripping effect on the article 10. But in no instance is the article 10 subjected to perforation or damage by its engagement with the fastening device and its consequent mounting on the supporting surface.

The illustration in Figure 4 compares in every detail to that shown and described in connection with Figures 1 and 2, with the exception that the former is straight for engaging a straight side rather than a corner of the arti- 55

cle. Therefore the same reference characters are used in connection with Figure 4.

In Figures 5 and 6 I have illustrated a simple form of fastening device indicated at 13 that may be provided with a stamped-out portion 14 which when bent downwardly, as shown in Figure 5, to leave the cut-out opening 15, is in the form of a sharp prong. The body portion may have an extension 13' with gripping indentations 14'. This sharp prong 14 may take the place of the usual separate fastening element and may thus be forced into the supporting surface such as indicated at 1, in such a manner that one edge or corner of the article 10 to be supported 15 may be clamped by the body portion 13 and its extension 13' with its gripping indentations 14' against the supporting surface 1. As will be seen, this type of fastening device also obviates the perforation or other damage to the surface 20 of the supported article. As shown in Figure 6 such a type of fastening device may be stamped out of a tape and wound up in a manner shown in Figure 6 for the purposes of dispensing or using. In the latter case the tape generally referred to as 16 may be stamped out in the manner shown in Figure 5 to form the separate fastening devices and the tape may further be partially perforated at different points 17 constituting the division lines between each separate fastening device.

Figure 3 illustrates one form of fastening device 18 with a stamped out portion 19 in the form of a sharp prong and bent over to leave the cut-out portion 20. This fastening device is particularly adaptable for use in holding a corner of the supported article between the upper wall 21 and the side walls 22.

Another form of fastening device is shown in Figure 7 and may be generally indicated as having a back plate 23 with an inwardly extending corrugation 24 to receive the rear surface of the supporting block 25. This back plate is provided with a plurality of cut-out portions 26 in the form of a sharp prong and these are shown bent 45 inwardly to leave the cut-out portions 27. The fastening device may also be provided with corner corrugations 28 and an intervening top wall 29. The front plate 30 may also be provided with one or more inwardly extending corrugations 31 50 for snug engagement with the front surface of the block 25 as the complete fastening device is slipped over either an edge or corner of the block and the sharp prongs 27 driven into the rear face of the block. The material of which this fastening device is made should be resilient so that there is a tendency for the front plate 30 to be sprung against the front face of the block. Thus as the article 10 to be supported is placed between the front surface of the block and the inner surface of the front plate 30, the article will be adequately held and supported without any resulting perforation or damage to the surface of the article.

Figures 8 and 9 represent a slightly different form of fastening device, including a resilient angular element 32, one arm of which is provided with either an integral or a separate fastening element 33 adapted to be driven into the supporting block 1. To the other arm of said angular resilient member may be secured by such means as a rivet 35 a vacuum cup 34 for holding the article in place against the upper surface of the supporting member 1. In this particular 70 instance the article to be supported is repre-

sented at 36 and may be a plate of glass or the like.

In Figure 10 the same type of vacuum cup is used and is secured by the same means 35, the only difference being that the member 32' 5 may be straight instead of angular and receive a similar fastening element 33.

In Figure 8 is shown the type of fastening device on the top of the upper side 37 of the board 1, as is shown in Figure 10. On the side 38 of the board is shown the type of fastening device illustrated in Figure 9, showing the angular member 32 to be of substantial length and provided at spaced points with several vacuum cups 34.

The foregoing description of several modifications of my invention illustrates the primary purpose of the invention to be a provision of a suitable fastening device that will lend itself to easy attachment to a supporting member and at the same time provide an adequate support for 20 any substantially flat article desired to be supported on the supporting element in snug engagement therewith and yet not be perforated or otherwise damaged in any way.

It is to be understood that while I have shown 25 various modifications of devices adapted to carry out the purpose of my invention, the invention is not in any wise limited to the particular modifications shown and described. For instance for selling purposes and for artistic purposes it will 30 be readily realized that the attachment devices may take the form of artistic designs and that the attachment devices may be either stamped out in such designs or have such artistic designs 35 impressed or painted thereon.

I claim:

1. A fastening device for clamping an article to a supporting surface without perforating or otherwise damaging said article, said device comprising a metallic strip having its center portion stamped out into a prong-shaped member which during use of the device is bent at an angle to the two end portions of said strip and is forced into said supporting surface adjacent to said article, one of the end portions of said strip having an irregular contour forming a projection from the body of said strip, an indentation formed in said projecting portion for gripping said article and maintaining it in fixed relationship with its supporting surface and the other end portion of said strip having an indentation complementary in shape to said projection.

2. A fastening device for clamping an article to a supporting surface without perforating or otherwise damaging said article, said device comprising a metallic strip having its center portion stamped out into a prong-shaped member which during use of the device is bent at an angle to the two end portions of said strip and is forced into said supporting surface adjacent to said article, one of the end portions of said strip having an irregular contour forming a projection from the body of said strip, and an indentation formed in said projecting portion for gripping said article and maintaining it in fixed relationship with its supporting surface, and the other end portion of said strip having an irregular contour complementary in shape to said first mentioned end portion.

3. A composite roll of fastening devices for 70 clamping articles to a supporting surface without perforating or otherwise damaging said articles, said roll comprising an elongated metallic ribbon consisting of a plurality of the fastening devices joined together to form said ribbon but having 75

perforations at the boundary line of each of said devices such that one or more of the devices may be removed from the roll as needed, and each of said fastening devices having a stamped-out prong-like center portion for insertion in said supporting surface and having one of its end portions indented to provide a gripping surface for holding the article to its supporting surface.

4. A fastening device for clamping an article

to a supporting surface without perforating or otherwise damaging said article, said device comprising a metallic strip the center portion of which is stamped out to form a prong for insertion in said supporting surface, the two end portions of said strip being irregularly and complementarily shaped and one of said end portions having an indented gripping surface.

FREDERICK K. HERSCHEMANN.
